UNITED STATES PATENT OFFICE.

WILLIAM BASKIN ALFORD AND EDWIN P. ALFORD, OF SUMTER,
SOUTH CAROLINA.

CUSPIDOR.

SPECIFICATION forming part of Letters Patent No. 792,872, dated June 20, 1905.

Application filed June 25, 1904. Serial No. 214,145.

To all whom it may concern:

Be it known that we, WILLIAM BASKIN ALFORD and EDWIN P. ALFORD, citizens of the United States, residing at Sumter, in the county of Sumter and State of South Carolina, have invented new and useful Improvements in Cuspidors, of which the following is a specification.

This invention relates to flushing cuspidors suitable particularly for the use of dentists; and it relates especially to that class of such cuspidors in which the bowl has a tubular rim from which the water is discharged.

The object of the invention is to produce a device improved with respect to the means for delivering the water. A slot or narrow opening is formed in the rim of the cuspidor, near the top thereof, through which the water is discharged in a thin sheet into the bowl. Improved means are disclosed for varying the size of the slot or opening, also for supplying water to the spittoon.

The spittoon is particularly designed to be used in connection with a water-motor, and the waste water from the motor is utilized to flush the spittoon. A connection is, however, provided whereby the spittoon may be flushed by the admission of water directly from the water-supply pipe without going to the motor.

In the accompanying drawings, Figure 1 is a vertical sectional view through the cuspidor and the supply and waste pipe connections. Fig. 2 is an elevation which also shows the direct connection between the water-supply pipe and the cuspidor. Fig. 3 is a detail in section of a modified form of spittoon.

Referring specifically to the drawings, 6 indicates the waste-pipe from a motor, (not shown,) and 7 a supply-pipe thereto. The waste-pipe acts as a support for the cuspidor, to which it is connected by a supply branch 8 and a waste branch 9. The branch pipe 8 leads from the pipe 6 and has a rising portion 10 connected to the rim 11 of the cuspidor. An air-vent tube 12 opens into the top of the pipe 10 and has for its purpose to allow the escape of any air which becomes confined in said pipe. The tube 12 extends vertically

to a sufficient height to prevent the overflow of any water therefrom. As the water falls in the waste-pipe 6 from the motor it carries with it a certain amount of air which it is necessary to remove before the water is discharged into the cuspidor; otherwise the sheet of water delivered thereinto will not be continuous and will contain objectionable breaks or spaces and will not flow noiselessly. The rising portion 10 permits the escape of any air carried down by the water, which air seeks the top of the pipe and escapes through the tube 12.

The cuspidor comprises outer and inner bowls 13 and 14, respectively, and a tubular rim 11 is formed by substantially semicircular portions at the top of each bowl. The edges of these semicircular bowls lap at the top, producing a continuous slot or opening therebetween, as indicated at 15, and the water escapes through this slot or opening in a smooth continuous sheet. The two bowls have tubular waste-outlets, (indicated, respectively, at 13^a and 14^a,) and these tubes are threaded to screw outside of each other, as shown. Adjustment is thereby permitted to vary the size of the opening 15. It is obvious that if the inner bowl is screwed down the opening 15 will be widened, and vice versa. Minute holes 16 in the tube 14^a allow the leakage of any water which may remain between the bowls after the operation of the cuspidor is stopped.

The outer nipple 13^a screws into the trap-fitting (indicated at 17) which connects to the outlet-pipe 9. The trap-fitting has a leg which receives a screw-cap 19. Gold and the like dropped in the spittoon is caught in the trap and may be recovered by removal of the cap 19.

In the waste-pipe 6, between the junctions therewith of the branch pipes 8 and 9, is a cock 20, by manipulation of which the water may be turned on or off from the cuspidor, as desired. Evidently when the cock is opened the water will flow directly out through the waste-pipe and when closed wholly or partly a corresponding amount of water will pass through the pipe 8 and the cuspidor.

It is sometimes desirable to flush the spit-

toon without operation of the motor from which the waste-pipe 6 leads, and for this purpose a direct connection is made with the supply-pipe 7, as shown in Fig. 2. This connection includes a flexible pipe 21, the flow through which is controlled by a cock 22 and the end of which enters the side of the pipe 10, as indicated at 23. The water may thus be turned on or off to give a direct flow from the supply-pipe to the spittoon when desired. The flexible connection 21 is provided to enable the cuspidor to be raised or lowered, which may be effected by means not necessary to describe here, such means being found in connection with dental chairs of ordinary construction.

In the modification shown in Fig. 3 the bowl is single, as at 25, and the tube 11 is produced at the top thereof with a similar discharge-slot 15. This discharge-slot in both constructions is preferably located at the top of the rim, whereby the water flows over substantially the inner half of the rim and effects the removal of any matter deposited thereon.

25 A cuspidor constructed as above described will have a silent, smooth, and even flow of a sheet of water from the opening in the rim down the inside of the bowl to the outlet. The water is rid of air, so that no breaks or 30 sputtering occur. The adjustment permitted by the double-bowl construction allows a nice control of the water delivered without in any way breaking the continuity of the sheet of water delivered.

35 What we claim as new, and desire to secure by Letters Patent, is—

1. In a flushing cuspidor, in combination, inner and outer bowls having a water-space

therebetween and tubular rim-sections at the top of each, which rim-sections lap at their 40 upper edges, forming a contracted inwardly-directed slot therebetween, a supply-inlet to said space, and a waste-outlet from the inner bowl.

2. A double bowl for a flushing cuspidor, 45 comprising inner and outer parts with a water-space between, the outer part having at the top a rim-section the upper edge of which is directed inwardly, and the inner part having at the top a rim-section the upper edge of 50 which is directed outwardly and located under and adjacent to the edge of the said rim-section of the outer part, producing a narrow inwardly-directed slot at the top of the rim, and both of said parts having at the bottom 55 outlet-pipes which screw into each other.

3. The combination with a main pipe, of a bowl having an inlet at the top and an outlet at the bottom, branch pipes connecting said main pipe and the inlet and outlet respectively, 60 and a cock in the main pipe between the junction therewith of said branch pipes whereby a current of water flowing through the main pipe may be partially or wholly deflected to flow through said bowl.

In testimony whereof we have signed our names to this specification in the presence of the subscribing witnesses.
